COOLING SYSTEM FOR MACHINE TOOLS

Charles F. Charlton and Mark A. Palmer, Jr.,
Manchester, Conn.

Application January 19, 1945, Serial No. 573,603

1 Claim. (Cl. 51—267)

1

This invention relates to a novel and superior cooling system for machine tools, such as grinding machines, milling machines, etc. The grinding or cutting contact of such tools with the work generates a considerable amount of heat and a circulating flow of cooling liquid is commonly provided over the tool and work for the purpose of keeping the temperature reduced to a safe maximum. It is desirable that foreign particles shall be separated from the spent liquid before it is again returned to the work and that the liquid shall be maintained below a predetermined maximum temperature.

In machines heretofore employed the spent liquid has been returned to a settling tank where the solids are precipitated and the liquid cooled before the latter is again returned to the work. This system of maintaining the liquid at predetermined temperature has proven inefficient due to the accumulation of solids on the refrigerating plates employed in the tank. Our invention contemplates the elimination of this difficulty by first separating the solids from the spent liquid by precipitation or otherwise and thereafter bringing the liquid to and maintaining it at the desired temperature by passing it through an enclosed channel including a refrigerating medium on its way back to the work. The production of such an improved method of circulating cooling liquid to machine tools and providing such liquid in clean and predetermined temperature condition to the work therein comprises the primary object of the invention.

The work operated on by grinding machines is required to be finished to a small tolerance and unless the work is kept at substantially uniform temperature during the grinding operation its expansion and contraction prevents the maintaining of such tolerance. In apparatus heretofore employed the temperature of the cooling liquid has varied as much as 15° and has been particularly affected by the gathering of sediment to a considerable thickness on the cooling system, thereby forming an insulation rendering the cooling effect very inefficient. We have discovered that by first removing the sediment and solids from the liquid and thereafter passing the clean liquid to the work through an enclosed channel including a refrigerating unit maintained at predetermined temperature we are able to keep the work at a plus or minus temperature within two degrees. The novel method resulting in this increased efficiency comprises an important object of our invention.

These and other features of the invention will 55 pipe of coil 44 and from thence through a pipe

2

be best understood and appreciated from the following description of a preferred embodiment thereof selected for purposes of illustration and shown in the accompanying drawing in which the one figure in the drawing is an elevation, partly broken away, of a machine embodying our invention.

In the drawing we have illustrated a grinding machine 10 including a grinding wheel 12. A liquid coolant is conducted to the wheel and work from a nozzle 14 in communication with a pipe 16, the flow being controlled by a valve 18. A coolant reservoir 20 is provided beneath the grinding wheel to receive the spent coolant. It is desirable that foreign particles, particularly including those picked up from the work, should be removed before the coolant is returned to the tool and for this purpose we have illustrated the reservoir as divided into a plurality of compartments 22, 23 and 24. The spent coolant flows from the tool into the first compartment 22 where most of the particles settle before the coolant flows over the baffle 25 into the compartment 23. Further settling of any remaining particles takes place in compartment 23 before the coolant flows over the baffle 26 into the compartment 24. The resulting relatively clean coolant is circulated from the compartment 24 back to the tool.

Efficient operation requires that the temperature of the coolant shall be at or below a predetermined maximum when it reaches the tool and work and the primary object of our invention resides in an improved method for efficiently maintaining such temperature within predetermined limits. To this end we pass the clean coolant from the compartment 24 through a refrigerating path on its return to the tool. As illustrated in the drawing, this path includes a plurality of pipes or tubes 28 surrounded by a refrigerating medium of predetermined capacity and temperature within a cylindrical heat exchanger 30.

Mounted on the reservoir is a pump 32 operated by a motor 34 and arranged to pump the coolant from the compartment 24 through pipes 36, 38, 28 and 16 to the nozzle 14. An economizer 40 is preferably employed in connection with the refrigerating system. A compressor (not illustrated) maintains a suction on the line 42 which passes in the form of a coil 44 back to the chamber 30 at 46. The vapor thus drawn from the chamber is compressed to a liquid and returned through a pipe 48 to and through a coil 48 within the

50 to the bottom of the chamber 30. A thermostatic expansion valve is provided at 52 and is connected by a tube 54 to a controlling expansion bulb at 56 whereby automatically to maintain a predetermined temperature within the chamber 30. The passage of the liquid refrigerant through the relatively cooler vapor refrigerant within the coils substantially cools the refrigerant liquid to the required degree on its return to the chamber 30. A refrigerant liquid level is maintained in the chamber 30 substantially as indicated at 58.

It will be apparent that the coolant is cooled with maximum efficiency as it passes through the several pipes 28 on its return from the compartment 24 to the tool and it will be furthermore apparent that the cooling system is adapted to operate and continue to operate with maximum efficiency on the coolant which is substantially freed from foreign particles before being circulated through the refrigerating path.

Having thus disclosed our invention what we claim as new and desire to secure by Letters Patent of the United States is:

A method of producing work to close tolerances in a machine tool by maintaining a predetermined constant temperature in the workpiece during

working operations thereon, which consists in conducting spent cooling liquid from the work to a separating chamber, separating the detritus solids from the liquid in the separating chamber, conducting the separated liquid through a refrigerating device maintained at a constant and definite temperature thereby cooling the separated liquid to a predetermined temperature, and discharging said liquid at said predetermined temperature onto the work.
